Attorney

UNITED STATES PATENT OFFICE.

JACOB K. ALTEMUS, OF PHILADELPHIA, PENNSYLVANIA.

KNOT CATCHER AND YARN CLEANER.

Application filed September 22, 1926. Serial No. 136,916.

This invention relates to improvements in yarn cleaning and knot catching devices.

In carrying out my invention I employ a supporting member or bracket and two bars 5 comprising base portions secured to the supporting member, and parallel extensions projecting from the base portions and forming a yarn passage between them.

An object of the invention is to provide a 10 device of novel construction which can be manufactured at low cost; which may be quickly adjusted to take care of different counts of yarn; and which will be strong and rigid and retain its adjustment when in 15 service.

Another object of the invention is to provide a device in which each bar may be readily inverted to present a new surface to the 20 yarn passage for wearing purposes.

With the foregoing and related objects in view the invention consists of the elements and the combinations of them hereinafter described and claimed.

In the accompanying drawings illustrating 25 the invention:

Figure 1 is a perspective view of a yarn cleaning and knot catching device embodying my invention.

Figure 2 is a side view of the device.

Figure 3 is a top view thereof.

Figure 4 is a front view thereof; and

Figure 5 is an end view of one of the bars which forms a part of the yarn passage.

Referring to the drawings, my improved 35 device as herein illustrated comprises a supporting member or bracket 2, upper and lower parallel bars 3 and screws 5 for securing the bars to the member 2.

The supporting member or bracket 2 may 40 be of any shape and size for its intended purpose. As herein illustrated, it comprises a shank portion 6 having a head 7 formed on one end thereof. The shank portion 6 is provided with a slot 8 for the reception of a screw by means of which the member or 45 bracket may be secured to a machine requiring the device when it is placed in service thereon.

The bars 3 are arranged in parallel relation and each bar comprises a base portion 9 and an extension 10 projecting therefrom.

Each bar 3, as herein illustrated, is formed from a bar originally square in cross section throughout its length and from which diagonally opposite corner portions are cut to 55 form the extension 10, leaving the base portions 9 square or rectangular in cross section.

This cutting away of the diagonally opposite corner portions of the original bars or blanks provides extensions 10 each of which 60 has a width greater than its thickness and each of which extends between diagonally opposite corners of its base portion 9, as clearly shown in Fig. 2.

The yarn passage 11 is formed between the 65 extensions 10, and the yarn is drawn through the passage 11 in the direction of the arrow in Fig. 2 when the device is in service. The extensions 10 are formed with relation to their bases 9 so that they diverge forwardly 70 from the region of the entrance to the yarn passage 11 as seen in Fig. 2. This construction provides opposing surfaces for the extensions 10 for cleaning the accumulation of 75 lint or dirt therefrom.

The extensions 10 are formed with opposite convex surfaces as shown in the drawings; and, in forming each extension 10 from the original square bar, the flat sides of the bar are not cut away between the corners 12 80 thereof and the lines 13, as shown in Fig. 5, so that when the two bars 3 are related to each other, as shown in the drawings, the yarn passage 11 will be formed between flat parallel surfaces for a short distance from the entrance thereto, and so that the rearward surfaces of the extensions 10 will extend substantially in the same plane at right angles to the direction of travel of the yarn for a short distance from the entrance of the yarn 90 passage 11 and thereby present obstruction walls to a knot or slab on the yarn passing through the device and thus effectually interrupt or stop the forward movement of the knot or slab.

The head 7 of the supporting member 2 is provided with a flat surface 14 and two parallel ribs 15 projecting therefrom, and the rectangular base portion 9 of each bar 3 has a pair of oppositely disposed parallel grooves 16 cut in opposite sides thereof. The ribs 15 and grooves 16 are so related that the pair of 95

grooves 16 on either side of either bar may be applied to the ribs 15 for the purpose of turning or inverting either bar. When either bar 3 is thus turned or inverted its extension 5 10 will occupy exactly the same relation to the extension 10 of the other bar as it did before it was inverted excepting for the reversal of its parts. Thus each bar 3 may be readily inverted to present a new wearing 10 surface for the yarn passage 11.

The base portion 9 of each bar is provided with an opening or hole 4 therein through which one of the screws 5 extends to secure the base portion to the supporting member 15 2, the screw 5 being screwed into the head 7 of the member 2. The diameter of the hole 4 is greater than the diameter of the body of the screw 5 extending therethrough to permit the bars 3 to be adjusted toward and from 20 each other when the screws 5 are loosened. This adjustment is provided to vary the space between the extensions 10 thus vary the yarn passage 11 to accommodate different counts of yarn. The engagement of the walls of the 25 grooves 16 with the ribs 15 preserves the parallel relationship between the bars 3 both during the adjustments thereof either toward or from each other and after the bars have been adjusted, they may be secured in their 30 position of adjustment by the tightening of one or both of the screws 5.

When it is desired to invert either bar 3 to present a new wearing surface to the yarn passage 11 it is merely necessary to remove 35 it and its securing screws 5 from the supporting member 2, give the bar 3 a half turn on its longitudinal axis, re-engage it with the member 2 and insert its screw 5 to secure it in its inverted position.

40 I claim as my invention:

1. The combination of a supporting member, and two bars comprising base portions secured to the member, and parallel extensions forming a yarn passage between them, 45 each bar being invertible, the member and the bars having opposing surfaces which engage each other and position the bars relatively to each other and prevent them from turning, and the opposing surfaces of the 50 extensions diverging forwardly from the region of the entrance to the passage in each position of each bar.

2. The combination of a supporting member, and two bars comprising base portions 55 secured to the member, and parallel extensions forming a yarn passage between them and forming corners at the entrance to the yarn passage, the opposing surfaces of the 60 extensions diverging forwardly from the region of the entrance to the yarn passage, and the rearward surfaces of the extensions extending substantially in the same plane for a short distance from the corners at the entrance to the yarn passage.

65 3. The combination of a supporting mem-

ber, and two bars comprising base portions secured to the member, and parallel extensions forming a yarn passage between them, each bar being invertible, the opposing surfaces of the extensions diverging forwardly 70 from the region of the entrance to the passage in each position of each bar, said extensions forming corners at the entrance to the yarn passage in each position of each bar, and the rearward surfaces of the extensions 75 extending substantially in the same plane for a short distance from the corners at the entrance to the yarn passage in each position of each bar.

4. The combination of a supporting member having a guiding rib, two bars comprising base portions arranged one above the other and parallel extensions forming a yarn passage between them, each bar being invertible, and each base portion having parallel 80 grooves in opposite sides thereof either of which may receive the rib, and means to secure each bar to the member with either groove of each bar fitted to the rib.

5. The combination of a supporting member having a guiding rib, two bars comprising base portions arranged one above the other and parallel extensions forming a yarn passage between them, each bar being invertible, and each base portion having parallel 85 grooves in opposite sides thereof either of which may receive the rib, means to secure each bar to the member with either groove of each bar fitted to the rib, and the opposing surfaces of the extensions diverging 90 forwardly from the region of the entrance to the passage in each position of each bar.

6. The combination of a supporting member having a guiding rib, two bars comprising base portions arranged one above the other and parallel extensions forming a yarn passage between them, each bar being invertible, and each base portion having parallel 95 grooves in opposite sides thereof either of which may receive the rib, means to secure each bar to the member with either groove of each bar fitted to the rib, the opposing surfaces of the extensions diverging forwardly 100 from the region of the entrance to the passage in each position of each bar, and the rearward surfaces of the extensions extending substantially in the same plane for a short distance from the entrance to the yarn passage in each position of each bar.

7. The combination of a supporting member, and two bars comprising base portions secured to the member, and parallel extensions forming a yarn passage between them, each bar being invertible, each base portion being rectangular in cross section, and each 110 extension having a width greater than its thickness and extending between diagonally opposite corners of its base portion.

8. A bar for a yarn cleaner and knot catcher, comprising a base portion, rectangular in 115

cross section, and an integral extension having a width greater than its thickness and extending between diagonally opposite corners of the base portion.

5. 9. A bar for a yarn cleaner and knot catcher, comprising a base portion, rectangular in cross section, and an integral extension hav-

ing a width greater than its thickness and extending between diagonally opposite corners of the base portion, the base portion ¹⁰ having parallel grooves in opposite sides thereof.

In testimony whereof I affix my signature.
JACOB K. ALTEMUS.
